UNITED STATES PATENT OFFICE

1,922,337

TRACK AND SUPPORT THEREFOR

Kenneth J. Tobin, Chicago, Ill., assignor to Camel Company, Chicago, Ill., a Corporation of Illinois

Application July 20, 1931. Serial No. 551,910

2 Claims. (Cl. 16—94)

This invention relates to tracks for sliding car doors and to the supports for said tracks.

Tracks for supporting freight car doors for sliding movement are customarily supported upon a car underframe by means of track brackets.

5 These brackets are secured to the side sills of the underframe and support and maintain the tracks through the medium of rivets passing through the brackets and the tracks. It is necessary, therefore, in so supporting tracks, to provide holes in the brackets, to drill holes in the tracks and to rivet the tracks and brackets together. There is entailed, consequently, by this mode of supporting tracks expense in the cost of rivets, drilling of holes and cost of assembly.

10 The present invention eliminates the above steps necessary for the support of the tracks and effects definite economies in construction.

It is an object of this invention to provide tracks adapted for use with sliding doors for railway house cars and to support said tracks so that direct connection between said tracks and the cars is obviated.

15 A further object is the provision of tracks for sliding car doors adapted to be supported and maintained in position by means of supporting brackets.

An object, also, is the provision of tracks and track brackets for sliding car doors, said brackets being capable of supporting said tracks without the use of rivets or the like.

20 Another object is the provision of tracks and track brackets for sliding car doors, said tracks being adapted for assembly with said brackets by sliding movement.

25 A further object is the provision of tracks and track brackets for sliding doors adapted to have interlocking engagement whereby the tracks are maintained by said brackets in position to support said doors without the use of additional means to secure said tracks.

With these and other objects in view, which will become apparent as the description proceeds, the invention comprises the novel constructions and combinations hereinafter described and more particularly pointed out and defined in the appended claims.

In the drawing:

Figure 1 is a fragmentary elevation of a house car to which one embodiment of the invention is applied.

Figure 2 is a vertical section taken on line 2—2 of Figure 1.

Figure 3 is a sectional view similar to Figure 55 2, showing a modified construction.

Figure 4 is a vertical section taken on line 4—4 of Figure 1.

Referring to the drawing there is disclosed a fragmentary portion of a railway house car 10 provided with the customary opening 11 adapted to be closed by means of a sliding door 12, supported for movement to and from closed position upon a track 13. The door is supported for movement upon the track by means of a plurality of spaced hangers 14—14 provided with rollers 15 positioned in engagement with the track. Supporting the track in proper position upon the car is a plurality of intermediate track brackets 16 which are secured preferably to the side sills 17 by means of rivets 18.

In the embodiment of the invention illustrated in Figures 1, 2 and 4 of the drawing the track 13 embodies a thread portion 19 from which a substantially right angular flange 20 extends.

The flange 20 is preferably provided with a substantially horizontally extending flange 21. The intermediate brackets employed to support the track 13 are clearly illustrated in Figures 1 and 2 of the drawing. Each of these brackets comprises the attaching portion 22 and is formed

20 with a substantially vertical recess 23 providing portions 23^a and 23^b embracing the vertical track flange 20 and a substantially horizontal communicating recess 24 providing a flange 24^a which, together with the portion 23^a, embraces the horizontal track flange 21. The recesses 23

25 and 24 bear substantially the same relationship as the vertical and horizontal flanges provided on the track. In other words, the composite contour of the recesses provided in each intermediate bracket corresponds substantially to the contour of the vertical and horizontal flanges of the track.

30 In addition to the intermediate track supporting brackets there is provided end supporting brackets 25 for the track. Each of the end supporting brackets is positioned in abutting

35 relationship with the corresponding end of the track so as to aid in preventing longitudinal movement of said track. The end brackets are provided with recesses 26 of substantially the

40 contour of the cross section of the track. The end brackets are provided, additionally, and preferably, with a section 27 extending above the track and serving as a stop for the door. This

45 section may advantageously be substantially I shaped in section, as clearly indicated in Figure 4 of the drawing. The end brackets, similarly

50 to the intermediate brackets, are preferably secured to the side sill 17 by means of rivets.

With the construction of track utilized in the

110

embodiment of the invention illustrated in Figures 1 and 2, it is preferable to employ a door, the panel of which is extended as indicated at 28 in back of the track 13. By this relationship 5 disengagement between the lower portion of the door and the track is avoided. In the modified embodiment of the invention illustrated in Figure 10 3 of the drawing a substantially channel shaped track 30 is employed. The track is provided with a horizontally extending flange 31. With this 15 form of track there is provided an outwardly downwardly extending flange 32 which may readily be utilized for interlocking engagement with an upwardly extending flange 33 provided preferably as an integral portion of a hanger 34 secured adjacent each corner of the door 35. By this construction it is apparent that disengagement 20 between the lower portion of the door and the track is avoided as readily as with the construction shown in Figure 2 of the drawing. To support the modified track 32 there is provided as in the embodiment of the invention illustrated in Figures 1 and 2, a plurality of intermediate track brackets and a plurality of end track brackets. 25 The intermediate brackets 36 are each provided with a substantially angular recess 37 forming portions 37^a and 37^b adapted to embrace the inner downwardly extending leg 38 and a portion 37^c cooperating with the portion 37^a to embrace 30 the flange 31 projecting from said leg. The end brackets used with the track 30 are substantially similar to those employed with the track 13, differing from the end brackets 25 only in the contour of the recess provided which conforms 35 to the contour of the track 30.

From the foregoing descriptions of the embodiments of this invention it is apparent that the intermediate brackets and one end bracket may be secured to the side sills 17 of the car and 40 the track assembled therewith by means of a sliding movement until it abuts the end bracket. The other end bracket may then be secured to the car in abutting relationship with the track. With this assembly it is apparent that the tread 45 of the track is supported directly by the brackets so as to prevent any downward movement of the

track and to carry the load of the door through the brackets directly to the underframe of the car. The brackets also abut against the vertical flange of the track and so maintain it against outward movement. The interengagement between the horizontally extending flange of the track and the bracket by means of the extension of said track into the recesses provided in the brackets prevents upward movement of said track relative to the brackets and firmly retains said track in position against possible rattling. It is clear, therefore, that the track is securely positioned without the necessity for riveting the track to the brackets. It is further apparent that the replacement of the track by a reverse process of the steps used in the assembly or placement of the track may readily be effected. 80 85 90

It is apparent that numerous changes and modifications may be made in the embodiments of the invention disclosed. All such changes and modifications are deemed to fall within this invention which is to be limited only by the scope of the claims appended hereto. 95

I claim:

1. In combination, a track, brackets for supporting said track, said brackets comprising portions embracing a vertically positioned flange of said track, a horizontal flange extending from said vertical track flange intermediate the edges thereof, one of said portions cooperating with a bracket flange to embrace said horizontal track flange, and means provided on said brackets for abutting the underside of the tread of said track to reinforce said tread against transverse bending. 100 105

2. In combination, a track, brackets for supporting said track, said brackets comprising portions embracing a vertically positioned flange of said track, an inwardly directed horizontal flange extending from said vertical track flange, one of said portions cooperating with a bracket flange to embrace said horizontal track flange, and means provided on said brackets for abutting the underside of the tread of said track to reinforce said tread against transverse bending. 110 115 120
